REMOTE-CONTROL SYSTEM FOR
RAILWAY SIGNALSThomas J. Judge, Rochester, N. Y., assignor to
General Railway Signal Company, Rochester,
N. Y.

Application July 29, 1944, Serial No. 547,176

13 Claims. (Cl. 177—353)

1

This invention relates to communication systems for the remote selective control of the various lamps or indicators of route signals, yard track signals, and the like commonly used on railroads.

In connection with handling traffic into the various side tracks for storage yards, freight switching yards and the like, it is desirable to selectively control from a distant yard office or similar control point the indicating lamps or like indicators of a yard signal located at a convenient point with respect to the entrance to the yard, so that the engineer of a train approaching the yard may be instructed where to put his train. This is a typical application of a multiple aspect signal remotely controlled from a distant control point in accordance with this invention, but the same functions and mode of operation may be utilized for the control of route signals and the like.

The primary object of this invention is to provide a simple and effective organization for the selected remote control of yard signals over a minimum number of line wires and with a small number of relays of the conventional type.

Another object of the invention is to simplify the manipulation of a system of this character, and facilitate its use by office personnel in a yard office without special training.

Various other objects, attributes and characteristic features of the invention will be in part apparent, and in part pointed out as the description progresses.

Generally speaking, and without attempting to define the nature and scope of the invention, it is proposed to control a yard signal over a pair of line wires in accordance with the number and polarity of pulses in a selecting code, using a manually operable switch to determine the polarity, and a conventional telephone dial switch to determine the number of impulses. It is also proposed to provide a bank of stepping relays and associated control relays and circuits for selectively governing the control or lighting circuits of the signal in accordance with the code transmitted, such an organization of conventional relay structures being considered to be more suitable for railway use than step-by-step switches or like mechanical devices.

The accompanying drawings illustrate in a simplified and diagrammatic manner certain specific embodiments of the invention, the parts and circuits being illustrated in a manner to facilitate an explanation and understanding of the nature and mode of operation of the invention, rather

2

than to illustrate the detail construction and arrangement of parts preferably employed in practice.

In the drawings, Fig. 1A and Fig. 1B show respectively the code transmitting apparatus at the control point and the equipment at the field location for receiving the selecting codes and governing the control circuits of the yard signal accordingly; Fig. 2 illustrates a modified organization of the code sending or calling equipment; and Fig. 3 is a general explanatory view of a typical yard track signal or indicator of the type contemplated.

In the interests of simplifying the illustration, 15 various contacts of the relays and other parts have been illustrated diagrammatically, and the symbols (+) and (—) are conveniently employed to designate connections to the opposite terminals of a battery or other suitable source of 20 operating current.

The signal or indicating means governed in accordance with this invention may take various forms, and the signal S indicated in Fig. 3 and similar to that disclosed for example in the patent 25 to P. M. Gault, No. 1,875,587, September 6, 1932, is merely typical. This type of yard signal comprises a number of light projecting units designated 2, 16 being shown, each having a distinctive number or like insignia formed on its cover 30 glass, or other part of the optical system, in such a way that when the associated electric lamp is lighted, the desired indication of a track number or the like is displayed. For example, these light units may be of a form disclosed by the patent 35 to S. M. Day, No. 1,548,984, August 11, 1925. The signal as a whole is provided with a suitable visor or sunshade 3 to minimize objectionable phantom indications by reflected external light.

The purpose of the present invention is to provide facilities for selectively closing control or lighting circuits for the indicators by code transmission over a pair of line wires. One form of means in the yard office or similar control point for creating the desired code, illustrated in Fig. 40 1A, comprises a conventional telephone dial switch DS of the well known construction commonly used in telephone dial switching systems, and a three-position hand switch or key K. The telephone dial switch comprises the usual rotatable disc 5 with the usual finger holes, back of which are the fixed numbers. In the arrangement shown, provision is made for selectively controlling 16 different indicating lamps; and since polarity as well as the number of pulses is 45 employed for selection purposes, the dial switch 50 55

has only 8 openings, each of which relate to two different signal codes such as 1-9, 2-10, 3-11, etc. A normally closed contact 6 intermittently opened by an operating cam 7 of the dial switch DS in the usual way is included in one of the line wires L1, so that when the dial switch is operated in the usual way to dial a given number, this line wire L1 is intermittently opened the same number of times.

The contacts 8, 9 shown conventionally and operated by the three-position key switch K govern the continuity and polarity of the connections from a battery B, or other suitable source of current to the line wires L1, L2. An indicating lamp 12 connected across the resistance 13 in the line wire L2 is preferably employed to indicate when current is flowing in the line circuit.

Referring to the field apparatus shown in Fig 1B, this comprises a three-position polar line relay F, biased to its intermediate position, a quick-acting repeater relay FP, positive and negative conditioning slow-acting relays PSA and NSA, a suitable light control relay LC, a bank of four stepping relays V1, V2, V3, V4, a repeat stepping relay VR, and a half-step relay VP. All of these relays, except the polar line relay F, are of the conventional telephone type, commonly used in code communication systems for centralized traffic control on railroads, these relays operating quickly to open and close their contacts unless made slow-releasing by copper slugs or the equivalent in accordance with the usual practice. A suitable source of current, assumed to be an alternating current source with terminals BX and CX is provided for lighting the indicating lamps of the signal when their respective control circuits are closed.

Typical operation.—Referring to the form of the invention shown in Figs. 1A and 1B, the parts and circuits are illustrated in the normal condition under which no indication for the yard signal is displayed. The line wires L1, L2 are de-energized, and all of the relays of the field apparatus are deenergized.

Assuming that the yard master or other operator desires to instruct the next train to move to yard track 2, for example, he operates key switch K to the upper position, since that position is for the group of numbers 1 to 8 including 2, and then dials the number 2 on the telephone dial switch. The operation of the key switch K and its contacts 8, 9 connects the battery B to the line wires L1, L2 with one polarity, conveniently considered to be (+). This energizes line relay F at the field location to move its contact fingers 15, 16 from the middle biased position shown to the right-hand position, thereby establishing a pick-up circuit for the positive selecting or conditioning relay PSA from (+), through contact finger 16 of relay F to the right, back contact 17 of relay NSA, relay PSA to (-). This energization of relay PSA and closing of its front contact 18 energizes the light control relay LC over a circuit from (+), through front contact 18 of relay PSA, bus 19, back contacts 21, 22, 23 and 24 of relays V4, V3, V2 and V1, respectively, relay LC to (-). This energization of relay LC closes its front contact 26 to connect (+) to the polar contact finger 15 of relay F, thereby energizing its repeater FP over an obvious circuit.

This energization of relay FP, with relay LC energized, establishes a pick-up circuit for the half-step relay VP which may be traced from (+) through front contact 30 of relay LC, front

contact 31 of relay FP, bus 32, through back contacts 33, 34, 35, 36 of relays V4, V3, V2 and V1 respectively, relay VP to (-).

This energization of the relay VP and closure of its front contact 38 establishes a stick circuit for this relay which may be traced from (+), through front contact 30 of relay LC, front contact 38 of relay VP and through the back contacts 33 to 36 of relays V4 to V1, the same as in the pick-up circuit for this relay. Also, the closure of the front contact 39 of the relay VP prepares an auxiliary stick circuit for this relay including the back contact 31 of the line repeater relay FP.

15 After this conditioning operation, which occurs as soon as the hand switch K is operated, the first time the contact 6 in the line wire L1 is opened by the dial switch DS for the first count of the code under consideration, the line relay F and its repeater FP are deenergized; and this picks up the first step relay V1 over a circuit from (+), through front contact 40 of relay LC, back contact 41 of relay FP, front contact 42 of relay VP, back contact 43 of relay V2, and lower winding 20 of relay V1 to (-). The step relay V1 is held up by a stick circuit from the bus 19, connected to (+) through front contact 18 of relay PSA, through back contact 46 of relay V2 and front contact 47 of relay V1, and its upper winding to (-). During this time the half-step relay VP is held up by its auxiliary stick circuit above mentioned.

The pick-up circuit for the light control relay LC is broken at the back contact 24 of the step relay V1, but while the line relay F is deenergized, this relay LC is held up by a stick circuit which may be traced from (+), through back contact 48 of relay FP, front contact 49 of relay PSA, front contact 50 of relay LC, and relay LC to (-). 25 The next time the line circuit is energized and the relay FP opens its back contact 48, the relay LC is deenergized; but this relay LC is sufficiently slow-releasing to maintain its armature and contact fingers in the attracted position during the relatively short time the line circuit is energized between the successive pulses of the counting code.

When the contacts 6 of the dial switch close after this first count, the resultant energization of the line relay F and its repeater F cause a shift or deenergization of the relay VP ready for the next step. The relay VP is deenergized because its pick-up circuit and first stick circuit above traced are broken with the back contact 36 of step relay V1 now energized, and its auxiliary stick circuit through its front contact 39 and back contact 31 of relay FP is broken by the energization of relay FP.

The next opening of the line circuit by the operation of the contacts 6 of the dial switch for the second count, and the resultant deenergization of the relay F establishes a pick-up circuit for step relay V2 from (+), through front contact 40 of relay LC, back contact 41 of relay FP, back contact 42 of relay VP, back contact 51 of relay V3, front contact 52 of relay V1, and lower winding of V2 to (-). This energization of relay V2 and opening of its back contact 46 breaks the stick circuit previously traced through the upper winding of the relay V1, to release that relay.

Since relay V2 is being picked up through a circuit including a front contact 51 of the relay V1, an auxiliary stick circuit for each stepping relay, controlled by the contact 54 of relay VP and a back contact 55 of the relay FP, is prefer-

ably employed to hold up the next preceding step relay when a step relay is energized, i. e., hold up relay **V1**, while relay **V2** is being energized, until such energization is completed and the line circuit is again energized to shift the relay **VP**. This auxiliary stick circuit in the case of relay **V1** may be traced from (+), through contact **18** of relay **PSA**, back contact **55** of relay **FP**, back contact **54** of relay **VP**, and front contact **56** of relay **V1** through its upper winding to (-). It can be seen that this auxiliary stick circuit for the step relay **V1** is closed, and the relay **V1** is held up during the period of energization of the relay **V2**, and is not released until the relay **FP** picks up during the next energization of the line circuit.

In the example of a 2 count assumed, after the second pulse and energization of the step relay **V2**, followed by the release of relay **V1**, further interruption of the line circuit ceases, and the line relay **F** remains steadily energized with the (+) polarity assumed. Under these conditions, the light control relay **LC** releases after a time, its pick-up circuit being broken at back contact **23** of relay **V2** now energized, and its stick circuit at the back contact **48** of relay **FP**. This deenergization of relay **LC** and opening of its front contact **26** in turn drops relay **FP**. The positive selecting relay **PSA**, however, is maintained energized through its pick-up circuit and the polar contact **16** of the relay **F** in its right-hand position.

Under these conditions, upon release of the light control relay **LC**, the primary **60** of the transformer **T** supplying current to the lighting circuits is energized from a suitable source of alternating current from **BX**, through front contact **61** of relay **PSA**, back contact **62** of relay **LC**, primary of transformer **60**, to **CX**. With the relay **PSA** energized and the repeat relay **VR** deenergized, the indicator **2** is included in the secondary circuit of the transformer by connections which may be traced from the upper terminal of said secondary **64**, wire **65**, back contact **66** of relay **VR**, front contact **67** of stepping relay **V2** now energized, lamp **2**, wire **68**, front contact **69** of relay **PSA** to the upper terminal of said secondary.

Thus, at the termination of the polar count code in question, the corresponding indicator lamp **2** is lighted; and this condition continues until the operator shifts the key switch **K** to the middle position to deenergize the line circuit and release line relay **F**, whereupon the positive selecting relay **PSA** is deenergized, and the stepping relay **V2** then energized is restored to its normal condition.

Similar circuits are involved in the operation of selecting signals for other counts of 1, 3, and 4 of the same polarity. If the key switch **K** is shifted down to the other position to energize the line circuit with the other or negative polarity, the negative selecting relay **NSA** is energized through the polar contact **72** of relay **PSA**. This negative selective relay **NSA** closes front contacts **73**, **74** and **75** in multiple with the front contacts **18**, **49**, **61** respectively of the relay **PSA**, so that the same stepping operations and energization of the transformer **T** occur with relay **NSA** energized, as previously described for relay **PSA** energized. The energization of the negative selecting relay **NSA** and the closure of its front contact **71**, however, connects different lamps to the secondary **64** of the transformer **T** for the same step relay then energized. For example, if the negative selecting relay **NSA** is energized with the

step relay **V2** energized, the indication lamp **10** is lighted instead of indicating lamp **2**, over a circuit which may be traced from wire **65**, through back contact **78** of repeat relay **VR**, front contact **79** of relay **V2**, lamp **10**, wire **80**, and front contact **77** of relay **NSA**.

Thus, the polarity of the pulses, as well as the number of pulses, determines the selection and provides for the control of twice as many indicators as could be governed in accordance with the number of pulses of a fixed polarity.

In the arrangement shown, provision is also made for operating the same step relays **V1** to **V4** for a second time to absorb counts 5, 6, 7 or 8. Briefly considering this repeat operation, during the energization of the line after the fourth stepping pulse, the relay **VP** is energized through front contact **33** of relay **V4** then energized, and the pick-up circuit for the step relay **V1** is prepared, so that this relay **V1** is energized for the second time on the 5th code pulse. This second energization of this relay **V1**, with relay **V4** also energized, closes a pick-up circuit for the repeat relay **VR** from (+), through front contact **83** of relay **V1**, front contact **84** of relay **V4**, and lower winding of relay **VR**. Relay **VR** is held up by a stick circuit readily traced through its front contact **85** to the bus **19** connected to (+) through front contacts **18** or **73** of relays **PSA** or **NSA**.

Thus when the stepping relays **V1** to **V4** are operated for the second time, corresponding with code counts 5, 6, 7 and 8, the repeat relay **VR** is energized, thereby shifting its contact fingers **66** and **78** to provide for the energization of a different group of indicating lamps for the same polarity and step relay energization. For example, if the step relay **V2** is energized for a count of 6, the lighting circuit for lamp **6** is established through front contact **66** of relay **VR**, if the positive selecting relay **PSA** is energized, while the lighting circuit for lamp **14** is completed through front contact **78** of relay **VR** if the negative selecting relay **NSA** is energized.

The organization of this invention avoids undesirable and improper operations by careless or accidental manipulation of the sending equipment. After a selecting code has been transmitted and the light control relay **LC** has released to energize the particular lighting circuit selected, the energizing circuits for the stepping relays are broken at the front contact **40** of this relay **LC**, so that any careless or idle movement of the telephone dial switch and intermittent interruption of the line circuit will not operate any additional stepping relays, or change the existing selection. In order to extinguish any indicating lamp or change to a different indication, the line circuit has to be opened long enough to release either the relay **PSA** or the relay **NSA** that may happen to be energized, thereby opening front contact **18** or **73** to break the stick circuit for the step relay then energized, and complete the pick-up circuit for the relay **LC** through the back contacts of the stepping relays.

It will be noted that the pick-up circuits for the relays **PSA** and **NSA** are interlocked, so that neither of these relays may be energized unless the other is deenergized. This assures that a change in the polarity of energization of the line circuit by operation of the key switch **K** will not change the existing signal indication. For example, if the step relay **V2** is energized with the relay **PSA** energized to establish a circuit for lighting indicating lamp **2**, as previously de-

scribed, a movement of the key switch S and a change in the polarity of energization of the line circuit will not change to the indicating lamp 10 having its circuit controlled by the relay NSA, since this relay NSA cannot pick up until relay PSA has released.

Each of the relays PSA and NSA is also provided with a stick circuit to maintain it energized if the contact finger 16 of the polar line relay F moves from one extreme position to the other, without remaining in the middle position long enough for the relay PSA or NSA then energized to release, these relays being slightly slow releasing to maintain their armatures and contacts in the attracted position during the relatively short times that the line circuit is deenergized during normal code transmission. This stick circuit for the relay PSA may be traced from (+), contact finger 16 of line relay F to the left, front contact 12 of relay PSA, and winding of this relay to (-). Consequently, a relatively quick movement of the key switch K from one extreme position to the other for any reason, and the resultant change in polarity of energization of the line circuit, will not shift to a different signal indication, nor change the then existing signal indication.

It will also be noted that the control or lighting circuits are not energized until the relay LC releases at the end of the counting code being sent. Consequently, there is no flashing of the lamps as the stepping relays are being operated to prepare the final selection circuits.

Modification.—Fig. 2 illustrates a modified form of the code sending or coding equipment designed to simplify the manipulation, minimize the chance for error, and indicate to the operator what particular signal is being displayed. In this modification, a number of openings for contact receptacles, similar to the conventional telephone jack and designated 90, are arranged around the dial switch, with two such openings opposite each finger hole of the dial. The numbers identifying the different signal indications are associated with these contact receptacles, rather than the finger holes on the telephone dial. A suitable plug or contact pin 91, constituting in effect a token, may be conveniently connected to the panel by a suitable chain 92 or the like and used to close spring contacts 93 shown conventionally, when inserted in one of the openings of these contact receptacles. The contacts 93 of the inner series of receptacles are connected to a relay PC and those for the outer series to another relay NC; and these relays PC and NC operate contacts 96, 97, 98, 99 to connect the battery B to the line wires L1 and L2 with positive and negative polarity by reason of the obvious circuit connections shown.

In this modified arrangement when the operator desires to display a particular indicator, he inserts the token 91 into the opening bearing a corresponding number, thereby closing the associated contacts 93 to energize either the relay PC or the relay NC, as the case may be, to determine the polarity of the code pulses required to select this particular indicator. The operator then puts his finger in the hole in the telephone dial opposite the location of the token, pulls the dial against the stop, and lets go. This transmits an appropriate number of pulses of the proper polarity.

The use of the token 91 in the various receptacles in this manner not only facilitates the selection of the polarity desired for the selec-

tion being made, but also affords a visual indication identifying the particular indicator for which the code was last transmitted. In other words, the operator can tell from the location of the token 91 what track indication is being displayed on the yard signal, assuming of course that after the token was positioned the telephone dial was operated, and the field equipment properly responded.

10 When the display of a track indication is no longer needed, the token 91 may be removed, whereupon the relay PC or NC, as the case may be, is deenergized to disconnect the battery from the line wires L1 and L2 and restore the field equipment to the normal condition shown, as previously explained.

Having thus shown and described one rather specific embodiment of the present invention, it is desired to be understood that the particular embodiment illustrated has been selected to facilitate description of the principles and operating features of the invention rather than the scope of the invention or the particular means to be employed in practicing the invention and that various changes, modifications and additions may be made to adapt the invention to the particular problem encountered in practicing the same without departing from the spirit or scope of the invention, except as demanded by the scope of the following claims.

What I claim as new is:

1. In a system for the remote selective control of the indicators of a multiple aspect railway signal over a pair of line wires extending from a control point to the field location of said signal, a telephone dial switch at the control point for applying a selected number of pulses to said line wires, manually operable pole-changing contacts at the control point for governing the polarity of such pulses, and apparatus at the field location responsive to the number and polarity of code pulses comprising, a plurality of circuits for governing the indicators of said signal, means responsive to the polarity of the code pulses for selecting between two groups of said circuits, a bank of stepping relays energized one at a time in response to the successive deenergizations of said line circuit for selecting between the individual circuits of the selected group in accordance with the number of the pulses, and means whereby a sudden change in polarity of energization of said line wires will not change the indicating aspect of said signal.

2. In a system for the remote selective control of different indications of a multiple aspect railway signal, a pair of line wires extending from a control point to the field location of said signal, means at the control point including manually operable pole-changing contacts and a telephone dial switch for energizing said line wires with a selected number of current pulses of one selected polarity, a plurality of control circuits for separately governing the indications of said signal, means including a bank of stepping relays responsive to the polarity and number of pulses applied to said line wires for selecting one of said lighting circuits, means responsive to a sustained energization of said line wires for energizing the particular control circuit selected, and means for preventing pole-changing of the energy on said line wires after the first of a series of impulses changing the indicating aspect of said signal.

3. In a system for remotely controlling the various indications of a multiple aspect railway signal over a line circuit extending from a distant

control point, means at the control point including a telephone dial switch for applying impulses of a selected number and polarity to said line circuit and for thereafter maintaining said line circuit energized until manually restored to normal, a plurality of control circuits for the indications of said signal, means at said signal including a polar line relay and a bank of stepping relays for selecting the particular one of said control circuits in accordance with the number and polarity of impulses transmitted and for energizing said selected control circuit so long as said line circuit is thereafter maintained energized, and means for preventing a change of polarity of the impulses after the first impulse producing any effect upon the indication to be displayed.

4. In a system of the character described for governing the indications of a multiple aspect railway signal over a pair of line wires from a distant control point, a plurality of control circuits for governing the indications of said signal, conditioning relays selectively energized in accordance with the polarity of initial energization of said line circuit for selecting between two groups of said control circuits, a bank of stepping relays energized one at a time in response to the successive pulses applied to said line circuit regardless of their polarity for selecting individual control circuits of the selected group, and means responsive to a sustained energization of said line circuit following the transmission of the code pulses of the selected polarity and number for energizing the control circuit selected so long as said line circuit is energized.

5. In a system of the character described for the remote selective control of the different indications of a railway signal, a line circuit extending from a control point to the location of said signal, a polar line relay connected to said line circuit, two conditioning relays respectively energized in response to the energization of said line relay with a corresponding polarity only if the other conditioning relay is then deenergized, a bank of stepping relays energized one at a time in response to the successive operations of said line relay regardless of polarity, and a plurality of control circuits for the indications of said signal selectively closed by contacts of said conditioning relay and said stepping relays.

6. In a system of the character described for the remote selective control of indications at a railway signal over a line circuit from a distant control point, means for rendering effective a particular indication of said signal in response to the sustained energization of said line circuit following transmission of code pulses of a selected number and polarity, code sending means at the control point for applying code pulses to said line circuit including a telephone dial switch for intermittently opening said line circuit a predetermined number of times in conformity with the finger hole of the dial used, relay means operable to energize said line circuit with a selected polarity, and means set manually to different selected positions for designating the finger hole of the dial to be used and for also selectively operating said relay means.

7. In a system of the character described for governing the indications of a multiple aspect railway signal in accordance with the number and polarity of pulses transmitted over a line circuit from a distant control point, code sending means at the control point for intermittently energizing said line circuit in accordance with a selected code comprising, a panel containing a

plurality of pairs of holes, a telephone dial switch associated with said panel and including a finger hole for each of said pairs of holes and for intermittently opening said line circuit the particular number of times corresponding with the finger hole in the dial used, means including a token movable to a particular pair of holes for identifying the finger hole of the telephone dial switch to be used and to a particular hole of such pair for selectively determining the polarity of energization of said line circuit, whereby the location of said token after each operation shows which indication of the signal was last selected, and multiple aspect railway signal means controlled over said line circuit by said code sending means.

8. In a system of the character described for selectively controlling the indications of a multiple aspect railway signal in accordance with the polarity and number of pulses transmitted over a line circuit from a distant control point, the combination with apparatus adjacent the signal including a bank of stepping relays for rendering effective a particular indication of said signal in accordance with the number and polarity of the impulses last transmitted over the line circuit, of manually operable means governing the impulses applied to said line circuit and comprising, a telephone dial switch, a plurality of token receptacles relating to the different indications of said signal and arranged in two rows around the rotary dial of said telephone dial switch and opposite the finger holes in said dial, and means governed by the insertion of a token in any receptacle of each of the different rows for determining the polarity of the pulses applied to the line circuit by operation of said telephone dial switch, whereby the location of the token is indicative of both the number and polarity of the impulses transmitted.

9. In a system for the remote selective control of a number of signal indicators over a pair of line wires from a distant control point, manually operable means for applying a selected number of pulses to said line wires of a selected polarity, a repeater line relay at the field location responsive to the energization of said line wires regardless of polarity, a plurality of control circuits for said signal indicators, means responsive to the polarity of the first impulse only of energization of said line wires for selecting between two groups of said control circuits, a bank of stepping relays energized one at a time for selecting between the individual control circuits of the selected group in accordance with the number of impulses transmitted, and means including a slow-release control relay for causing energization of the selected control circuit in response to a sustained energization of said line circuit following transmission of a series of selecting impulses.

10. In a system of the character described for selectively governing the indications of a multiple aspect railway signal from a remote control point over a pair of line wires, two sets of control circuits for governing the different indications of the signal, means including a bank of stepping relays energized successively in response to the intermittent energization of the line wires for selecting between control circuits of each of said two sets, means responsive to the polarity of the first energization only of said line circuit for selecting a particular one of said sets of control circuits, relay means actuated by a sustained energization of the line circuit after transmission

11

of a selecting code for energizing the particular signal control circuit selected, and means for preventing operation of said stepping relays while said relay means is actuated.

11. A system for selectively governing the indications of a multiple aspect railway signal from a remote control point over a line circuit comprising, manually operable means at the control point for energizing said line circuit with a variable selected number of time spaced pulses, means including a bank of stepping relays for selectively governing the indications of the signal in accordance with the number of pulses in the selecting code transmitted, and means responsive to a sustained energization of the line circuit after transmission of a selecting code for preventing further operation of the stepping relays until after said line circuit has been deenergized longer than a predetermined time interval, whereby an existing selection of a signal indication is not changed by pulsing of the line circuit after a particular signal indication has once been displayed.

12. A remote control system for railway signals comprising, a pair of line wires extending from the signal to a remote control point, a plurality of control circuits for the different indications of said signal, a bank of stepping relays for in part selectively governing said control circuits in accordance with the number of impulses applied to said line wires, a polar line relay for governing the operation of said stepping relays, two conditioning relays one for each possible polarity of energization of said line wires, a pick-up circuit for initially energizing that one of said conditioning relays during the first impulse of a series of impulses which corresponds in polarity to that impulse, and a stick circuit for each of said conditioning relays for holding the energized conditioning relay energized when the energization of said line relay is changed to the other

12

polarity, and means for controlling said control circuits by said stepping relays and said conditioning relays.

13. In a signal system of the character described for governing the indication of a multiple aspect signal from a remote point over a pair of line wires, two sets of control circuits associated with said signal, polarity responsive means responsive to the polarity of the first of a series of impulses transmitted over said line wires, stepping relays for counting the number of impulses of such series, means for selecting a particular set of said control circuits depending on the condition of said polarity responsive means, means including said stepping relays for selecting a particular control circuit of the selected set, means responsive to the termination of said series of impulses for energizing the selected control circuit of the selected set, and means for transmitting a series of impulses over said line wires of a number and with the first impulse of a polarity depending on the final aspect to be displayed
